CHARCOAL GRILL

John A. Riordan, Denver, Colo.

Application July 12, 1950, Serial No. 11,084

Term of patent 7 years

(Cl. D81—10)

To all whom it may concern:

Be it known that I, John A. Riordan, a citizen of the United States and a resident of the city and county of Denver, State of Colorado, have invented a new, original, and ornamental Design for Charcoal Grills, of which the following is a specification, reference being had to the accompanying drawing, forming a part hereof.

Figure 1 is a perspective view of a charcoal grill, showing my new design in closed position for cooking;

Figure 2 is a perspective view thereof in open position for supporting articles; and

Figure 3 is a section taken on the line 3—3 Figure 1.

I claim:

The ornamental design for a charcoal grill, as shown.

JOHN A. RIORDAN.
